STOCKING

Max Junghans, Boonton, N. J., assignor to Van Raalte Company, Inc., New York, N. Y., a corporation of New York

Application March 19, 1951, Serial No. 14,548

Term of patent 7 years

(Cl. D47—7)

To all whom it may concern:

Be it known that I, Max Junghans, a citizen of the United States, residing at Boonton, in the county of Morris and State of New Jersey, have invented a new, original, and ornamental Design for a Stocking, of which the following is a specification, reference being had to the accompanying drawing, forming part thereof.

In the drawing:

Fig. 1 is an elevational view showing the entire design.

Fig. 2 is a partial enlarged elevational view of the top portion of the stocking, showing the design in detail.

I claim:

The ornamental design for a stocking, substantially as shown.

MAX JUNGHANS.
